CLAIM

The ornamental design for a commercial lawn mower with grass bag, as shown and described.

DESCRIPTION

FIG. 1 is a perspective view of a commercial lawn mower with grass bag;

FIG. 2 is another perspective view thereof;

FIG. 3 is a side view thereof;

FIG. 4 is another side view thereof;

FIG. 5 is a rear view thereof;

FIG. 6 is a front view thereof;

FIG. 7 is a top view thereof; and,

FIG. 8 is a bottom view of the lawn mower showing the claimed design.

The broken lines shown in the drawings is included for the purpose of illustrating portions of the commercial lawn mower with grass bag and forms no part of the claimed design.

1 Claim, 8 Drawing Sheets
